UNITED STATES PATENT OFFICE

WARREN R. THOMAS, OF McMINTNVILLE, OREGON, ASSIGNOR TO A. I. THOMAS FURNACE COMPANY, OF McMINTNVILLE, OREGON

This invention relates to furnaces for burning finely comminuted fuel, and more particularly to furnaces for burning sawdust. A primary object of this invention is to provide a force draft furnace in which the conventional grate bars may be partly eliminated by using fire brick for a substantial part of the furnace floor. This materially reduces the cost of maintenance of the furnaces, because there are less grates to burn out. In addition, I use force draft which further reduces the tendency of the grates to burn out as quickly as they would with natural or stack draft. Further, more heat is generated and more power is developed by this arrangement.

Figs. 4 and 5 are plan and edge views, respectively, of one of the grates. Like numerals designate corresponding parts in all of the figures of the drawings.

In carrying out the invention, I build up a plurality of walls 5, of common red brick, in the ash pit, these walls lying in substantial parallelism with each other, and in spaced relation to each other, as shown. I top these walls with a row of fire bricks 6, which, in conjunction with the grates hereinafter described, constitute the floor of the furnace, the upper surfaces of the grates lying flush with the upper faces of the fire brick and presenting a plane surface upon which the sawdust is fed. The grates 6 have their

In the Dutch oven furnace, which is used in the majority of sawmills and wood working factories, the furnace is built in front of the boiler, and the fuel is fed into the furnace through a stoke hole in the top or arch, the heat being carried back over the bridge wall into the combustion chamber and thence through the boiler to the stack. This fuel, usually consisting of sawdust, piles up in a mound directly under the stroke hole, sometimes from three to five feet deep, and the air comes through the bare grates at the corners and around the edges of the pile. Therefore, the fire burns only from the edges and the top surfaces, while the whole pile of this hot fuel is supported by the grates in the center of the furnace. The result is that these grates become so hot, because of the lack of draft through them, that they become warped and sag down until they are useless, and have to be changed very frequently. The device of the present invention is intended to obviate the foregoing difficulties.

In the accompanying drawings.

Fig. 1 is a horizontal sectional view of a portion of a furnace constructed in accordance with the invention.

Fig. 2 is a plan view of one of the grate frames.

Fig. 3 is a transverse sectional view through one of the grate frames and grates, and the associated walls, and

PATENT OFFICE

RECORDATION OF THE REVENUE OFFICE OF THE STATE OF OREGON
REGON, ASSIGNOR TO A. I. THOMAS FURNACE
INNVILLE, OREGON
RECEIVED IN THE REVENUE OFFICE OF THE STATE OF OREGON
FURNACE GRATE

4, 1929. Serial No. 404,655. British Patent Office
Figs. 4 and 5 are plan and edge views, respectively, of one of the grates. Like numerals designate corresponding parts in all of the figures of the drawings.

In carrying out the invention, I build up, 55
a plurality of walls 5, of common red brick,
in the ash pit, these walls lying in substantial
parallelism with each other, and in spaced
relation to each other, as shown. I top these
walls with a row of fire bricks 6, which, in
conjunction with the grates hereinafter de- 60

scribed, constitute the floor of the furnace, the upper surfaces of the grates lying flush with the upper faces of the fire brick and presenting a plane surface upon which the sawdust is fed. The grates 6 have their end portions reduced, as indicated at 7, and these end portions rest upon the depressed transverse members 8, of rectangular grate frame

members 9. These grate frame members are provided with laterally extending flanges 10, which are embedded in the walls 5, between the fire brick and the common brick. The grate frames also comprise downwardly projecting portions 11, which aid in bracing the structure and rendering the whole firm. That portion of the grate frame which extends upwardly beyond the flanges aids in preventing the fire brick from crumbling.

The spaces between the several walls constitute air ducts 12, and these several longitudinally extending ducts communicate with a common cross duct 13, to which air may be supplied through any suitable conventional blower, from the communicating duct 14. The products of combustion pass over the bridge wall 15, to the combustion chamber 16, and thence to the boiler (not shown).

It is to be observed that the air is delivered into the ash pit from duct 13, at what is, in effect, the rear of the ash pit. This is the point where it is most needed. Furthermore, the delivery of the air at that point tends to blow the ashes toward the front A, of the furnace, so that they may be easily removed. 95

It will, of course, be understood that a single blower and duct 14 may be utilized to convey air to as many different longitudinally extending ducts 12 as the capacity of the blower will accommodate. The passage of

the forced draft between the walls 6, aids in cooling these walls, and consequently, aids in cooling the fire brick and the upward discharge of air, under forced draft, through all of the grates, keeps these grates sufficiently cool that they will not burn out, even after long periods of use.

Furthermore, by virtue of this construction, I am able to get even combustion over the whole area of the furnace, and I am able to control the amount of air supplied in such manner that accurate regulation of the fire is possible.

If it is desired to increase the output of heat, it is only necessary to increase the amount of fuel and air, while if I wish to decrease the heat of the furnace, this is easily accomplished by merely reducing the amount of air supplied to the furnace.

The device of the present invention uses only about one-third the amount of grates that the conventional natural draft furnaces use, and it gives a solid floor between the grates to receive the weight of the fuel. It is very much easier to keep clean than any other device of this nature with which I am familiar. It has the advantage over known furnaces that because the air is forced through the grates, the grates are kept cooler and clinkers are prevented from forming on the grates. It also has an advantage over devices of this nature employing upstanding nozzles, because in the present construction, the grates and the fire brick are on the same level, and the floor of the furnace can be cleared by shoving a slice bar over the floor.

With the right mixture of air, we are absolutely sure of securing a maximum heat value from the fuel. It is just as necessary to have the right volume of air to a fuel bed of sawdust under the varying moisture conditions existing in the sawdust, as it is with gasoline or any other high-grade fuel. This furnace is admirably adapted to handle fuel containing a very high moisture content. With it we can burn kiln dried shavings and sawdust from the log, which run from 50 to 75% moisture. The large grate area provides a large volume draft at low pressure. Where high pressure draft is utilized, the lightest and best fuel is carried off through the smoke stack, only partly burned. The only remedy for this is to deliver the air directly to the bottom of the fuel bed, and to have it under such control that it can be regulated in accordance with the moisture content of the fuel. With natural or stack draft it is nearly impossible to do this, especially with fuel that runs over 35 or 40% moisture.

It is to be understood that the invention is not limited to the precise construction set forth, but that it includes within its purview whatever changes fairly come within either the terms or the spirit of the appended claims.

Having described my invention, what I claim is:

1. A furnace of the character described, comprising a plurality of substantially parallel spaced walls forming ducts between them, the upper faces of which are composed of fire brick, rectangular grate frames having laterally extending flanges embedded in opposed walls, said grate frames comprising transversely extending rests at their opposite ends, and grates supported upon said rests with their upper faces substantially flush with the upper faces of the fire brick, said grates being sufficient in number to substantially close the tops of the ducts. 80

2. A furnace of the character described, comprising a plurality of substantially parallel spaced walls forming ducts between them the upper faces of which are composed of fire brick, rectangular grate frames having laterally extending flanges embedded in opposed walls, said grate frames comprising transversely extending rests at their opposite ends, and grates supported upon said rests with their upper faces substantially flush with the upper faces of the fire brick, said grates being sufficient in number to substantially close the tops of the ducts, and means for supplying forced draft to said ducts. 90

3. A furnace of the character described, comprising a plurality of substantially parallel spaced walls forming ducts between them, the upper faces of which are composed of fire brick, rectangular grate frames having laterally extending flanges embedded in opposed walls, said grate frames comprising transversely extending rests at their opposite ends, and grates supported upon said rests with their upper faces substantially flush with the upper faces of the fire brick, said grates being sufficient in number to substantially close the tops of the ducts, a transversely extending duct common to all of the first named ducts, and means for supplying forced draft air to said transversely extending duct. 100

In testimony whereof I affix my signature.

WARREN R. THOMAS.
